UNITED STATES PATENT OFFICE.

WILLIAM SHANNON, OF EAST CLEVELAND, OHIO.

VICE.

1,090,575.

Specification of Letters Patent. Patented Mar. 17, 1914.

Application filed October 26, 1912. Serial No. 727,855.

To all whom it may concern:

Be it known that I, WILLIAM SHANNON, a citizen of the United States, residing at East Cleveland, in the county of Cuyahoga and State of Ohio, have invented a certain new and useful Improvement in Vises, of which the following is a full, clear, and exact description, reference being had to the accompanying drawings.

10 The object of this invention is to provide a simple and efficient vise, adapted for ready attachment to a suitable support and capable of convenient and quick operation in clamping and releasing articles.

15 The invention is especially well adapted for embodiment in a plumber's or steam fitter's vise which may be easily attached to a plank, bench, or other support, and, when attached, is adapted to receive and clamp 20 pipes, or other objects, by a simple movement of an operating lever.

The invention is hereinafter more fully explained and the essential characteristics are summarized in the claims.

25 The drawings clearly illustrate a preferred form of my invention.

Figure 1 is a front elevation of the vise with the cover plate and operating lever removed; Fig. 2 is a front elevation, on a 30 reduced scale, of the vise complete; Fig. 3 is an edge view of the vise; Fig. 4 is a plan, partly broken away. The views 2, 3 and 4 are on the same scale. Fig. 5 is an enlarged longitudinal section of the operating lever; 35 Fig. 6 is a detail, being a fragmentary section of one of the clamping jaws, as indicated by the line 6--6 of Fig. 1; Fig. 7 is a sectional detail, showing the mounting of the operating cam.

40 Designating the different parts by numerals, 1 indicates the frame of the vise which includes a front plate or body 2 having an integral wall 3, projecting forwardly from its ends and bottom, thus providing a 45 recess 4 open in front and at the top. The front of the recess is normally closed by a cover plate 25, fastened by screws 26, or otherwise, whereby a casing is formed to carry the jaws and operating mechanism 50 thereof, as hereinafter explained.

Projecting rearwardly from the upper edge of the plate 2 and at right angles thereto is a plate or wing 5. The plates 2 and 5 are adapted to rest against the front edge 55 and top of a plank, for instance, or against two faces of any suitable support, to hold

the vise. To secure the vise to such support, I provide the plate 2 with ears 6 on its end through which are openings 7 adapted to receive bolts. Similar openings 8 in 60 the top plate 5 may receive bolts. In addition to such clamping feature, I prefer to provide a pair of clamps on the rear side of the plate 2. These clamps are made by brackets 9 integral with the plate and projecting rearwardly, and suitable thumb screws 10 screwing through these brackets. The thumb screws provide very simple means for temporarily securing the frame on a plank or the edge of a bench or table. 70

Pivoted mounted within the recess 4 are a pair of clamping jaws 11 and 12. These jaws are pivoted at 13 and 14, respectively, by studs mounted in the frame plate and cover plate. The jaws are formed as shown 75 in Fig. 1; that is, above the recess they have clamping portions, and within the recess have curved extensions 15 and 16, respectively. Between these extensions is a suitable double-faced cam 20, which is provided 80 with a rearwardly extending stud 21 journaled in the back plate 2 and with a stud 22 journaled in and projecting through the front plate, these two studs forming an axle for the cam. The stud 22 has a non-circular or angular extension or shank 23 to receive and be rigidly connected with the operating handle 30.

The operating handle referred to is shown in Figs. 2, 3 and 5. It has an angular or 90 other non-circular eye 31 extending over the non-circular shank 23, in front of the cover plate. The handle has its extreme portion formed as at 32, for convenient gripping by the operator's hand, and, intermediately, it has a recess 34, in which is mounted a pivoted locking dog 36. This dog is shown as normally pressed inwardly by a spring 37 secured to the handle. The nose 38 of the dog is adapted to engage with ratchet teeth or notches 40 formed on the front plate 25 in an arc about the shank 23. The outer end of the dog 36 is provided with a thumb piece 35 which furnishes means by which it may be forced inwardly. 100

From the construction described, it will be seen that when the lever 30 is moved upwardly about its pivot, it turns the cam 20 to spread the lower ends of the jaws and thereby force inwardly the upper ends to 110 clamp the article or stock between them. A suitable stop 41 limits the movement of the

lever into the releasing direction. The teeth 40 may be of ratchet form so that the dog nose 38 will trail over them under spring pressure, in which case it is only necessary to pull up the lever to effect the clamping, and to operate the dog by hand to release the lever, the latter being done by pressing inwardly with the thumb on the piece 35.

If the device is designed primarily for grasping pipe, or other round objects, there are preferably concave recesses in the faces of the jaw, as indicated at 50. These recesses are preferably serrated to form a good grip. In addition to the main recesses, there are preferably smaller recesses 51 in the jaws, designed to receive comparatively small articles. The small recesses, when fully open, are designed to take as large an object as the large recesses when fully closed, so that the range of the vise is from the closed small recesses to the open large recesses. When fully closed, the upper portions of the jaws above and below the small recesses 51 come very close together, so that flat or other shaped objects, may be placed in an up and down direction between the jaws and clasped thereby.

The body portions of the two jaws are preferably plates, which, opposite the recesses, are reinforced by additional plates on the opposite sides of the central portion. These additional plates are designated 54 and 55 in the drawing. They have recessed edges, which may be similar to those of the central portions, and are held on the central portion by dowel pins 57 and 58 carried thereby. These dowel pins properly position the reinforcing pieces, and the latter may be further secured by suitable screws 59. It is obvious that the reinforcing strips may, if desired, have various shaped recesses, less deep than the recesses of the central portions to provide different engaging faces, according to the character of the articles to be gripped. The reinforces may be case hardened to reduce wear, and are easily replaced when they have worn.

When my vise is put in place on a plank or other support and the lever dropped down to its normal depending position, the device is ready for receiving the stock. By having no superstructure above the engaging portion of the jaws there is nothing in the way of the workmen working at the bench or support, and the pipe or other stock may be placed in the jaws with the greatest ease. It is not necessary to slip the pipe endwise between the jaws, as is necessary when one of the jaws is supported from a cross head above. As the stock is inserted in the jaws from above, it results that any intermediate portion may be inserted as easily as the end portion of the stock, and also wear on the jaws from sliding of the

stock is avoided. As soon as the stock is placed in the jaws, which, as explained, may be done very quickly and easily, the lever 30 is drawn upwardly and the stock is automatically clamped. Whenever it is desired to release the stock, it is simply necessary to press inward the thumb piece 35 on the locking dog, the binding pressure thereon being preferably relieved by a slight upward pull on the lever.

Having thus described my invention, what I claim is:

1. In a vise, the combination of a casing consisting of a body and cover plate leaving a recess between them, a pair of jaws pivotally mounted within the recess and extending outside thereof, a double-faced cam within the recess between the jaws, said cam having a journal extending in opposite directions mounted in the frame and cover plate, the journal mounted in the cover plate extending in front of the cover plate in the form of a non-circular shank, a lever on said shank adapted to move the cam to spread the inner ends of the jaws, and rack teeth on the cover plate and a co-operating dog mounted in a recess in the lever for holding the lever in the position it assumes when the jaws are in gripping action.

2. In a portable vise, the combination of a casing having an upwardly opening recess, said recess having parallel sides, jaws pivoted within the recess when opening and having extensions fitting within the recess and guided by the parallel sides thereof, a cam within the recess between these extensions journaled in the casing and guided by the sides of the recess, a lever outside of the casing for rotating the cam, and means for securing the casing to a suitable support.

3. In a portable vise, the combination of a casing consisting of a body and a cover plate leaving a recess between them and a pair of jaws pivotally mounted within the recess and extending outside thereof, said jaws having extensions within the recess adapted to be guided by the sides of the recess a cam within the recess guided by the sides thereof, and pivotally mounted between these extensions, said pivot extending outside of the casing, a lever mounted on the extension of said pivot for rotating the cam, ears rigid on the casing, a rearwardly extending plate rigid on the casing, rearwardly projecting brackets secured to the casing and carrying clamping means whereby the vise may be removably secured to a suitable support.

4. In a vise, the combination of a casing consisting of a body and a cover plate leaving a recess between them, a pair of jaws pivotally mounted within the recess and extending outside thereof, reinforcing plates carried on the sides of said jaws outside of the casing, curved extensions integral with said jaws inside of the casing, a double faced

cam between these extensions journaled in the cover and in the casing, said cam lying substantially in the same plane with the extensions of the jaws, and a lever outside of the casing for rotating the cam to move the jaws.

5. In a vise, the combination of a casing consisting of a body and a cover plate leaving a recess between them, jaws pivotally mounted within the recess and extending outside thereof, curved extensions on the jaws within the recess, a double faced cam mounted between these extensions and having an angular projection outside of the casing, a lever on said projection, said extensions and the cam being so curved that the movement of the jaws is substantially equal upon a movement of the cam, ratchet teeth on the face of the cover, a dog pivotally carried by the handle engaging said teeth and adapted to be released by the thumb of the operator, ears projecting from the casing in a plane parallel in the back thereof, a rearwardly projecting flange, rearwardly projecting brackets, and thumb screws carried by the brackets.

6. In a vise, the combination of a frame

having a front plate with a wall, a cover providing an upwardly opening recess, rearwardly projecting brackets secured to the front plates, a clamping means carried by said brackets adapted to coöperate with the top plate to clamp the frame in place, a pair of jaws pivoted in the recess and extending outside thereof and having extensions inside the frame, a double faced cam between these extensions, said cam extension being curved so that the jaws move substantially the same distance upon a movement of the cam, a journal for said cam mounted in the front plate, a cover plate, said journal having an angular extension in front of the cover plate, a lever mounted on said angular extension and adapted to move the cam by swinging in a plane parallel with the cover plate, and means for locking the lever in the position it assumes when the jaws are in a gripping action.

In testimony whereof, I hereunto affix my signature in the presence of two witnesses.

WILLIAM SHANNON.
